[57] CLAIM

The ornamental design for a lavatory or the like, substantially as shown and described.

DESCRIPTION

FIG. 1 is a top plan view of a lavatory or the like embodying my new design;

FIG. 2 is a right side elevational view thereof, the left side being a mirror image of the right side shown;

FIG. 3 is a front elevational view thereof;

FIG. 4 is a bottom plan view thereof;

FIG. 5 is a cross sectional view taken on line 5—5 of FIG. 1;

FIG. 6 is a cross sectional view taken on line 6—6 of FIG. 1;

FIG. 7 is an enlarged fragmentary top plan view of a section of the lavatory rim; and

FIG. 8 is a cross sectional view taken on line 8—8 of FIG. 7.

FIG. 2
